UNITED STATES PATENT OFFICE.

FRANK B. REYNOLDS, OF DUBUQUE, IOWA.

IDENTIFYING DEVICE.

1,183,592.

Specification of Letters Patent.

Patented May 16, 1916.

Application filed January 10, 1914. Serial No. 811,359.

To all whom it may concern:

Be it known that I, FRANK B. REYNOLDS, a citizen of the United States, residing at Dubuque, in the county of Dubuque and 5 State of Iowa, have invented certain new and useful Improvements in Identifying Devices, of which the following is a specification.

The leading object of my invention is to 10 provide mechanical means for validating documents, with special reference to validating accident insurance policies at railroad stations, hotels, etc., whereby a traveler is enabled, personally, with a coin of 15 proper denomination to purchase a valid accident policy without application to other human agency.

The mode of construction and the manner 20 of operating whereby I accomplish the objects sought are fully set out in the following specification when read in connection with the drawings accompanying the same and forming a part hereof.

Figure 1 is a perspective view of my device. Fig. 2 shows a perspective view with 25 part of the casing and one of a pair of inking pads removed for the sake of clarity. Fig. 3 is a perspective view with one side of the channel and part of the casing removed, 30 showing the inside of the channel and the impression roller in position. Fig. 4 is a perspective view of the impression roller. Fig. 5 is the channel and the casing of the 35 channel removed. Fig. 6 is the hinge plate detached.

Like characters of reference denote corresponding parts in each of the drawings.

Having reference to the drawings 2 designates the top board, 4 the sides, 5 the base 40 and 6 the rear of outer casing. Through the top of the casing is an opening 8, through which a plunger shaft 10 is adapted to operate. Said plunger shaft is provided with an operating handle 12, a cross bar 13 for 45 means of guidance and stop and said shaft is surrounded by a coil spring 14. The bottom of plunger shaft 10 of which cross bar 13 forms a part, tapers to a plunging or driving end 15. In the casing near the forward end is a partition 16 and against the partition is secured a plate 18 through which an arm of the impression roller is operated. To the inside of partition 16 is attached a 50 side plate 7 to which is hinged a guide plate 55 20 having in its center a groove or chute

21 in which the coin is made to travel and operate the impression roller.

Plates 7, 9 and 11 form a coin channel by which the coin is guided as it is forced through the channel by the plunger 15. The 60 channel guides the coin till it engages the groove 21 in the hinged plate 20 and then plate 11 and front plate 50 branch off substantially at right angles to allow the outward play of the hinge plate 20, when the 65 coin is guided by the groove 21 in conjunction with the side plate 9 until it is forced into the receiving box below.

For the purpose of stamping the name upon the policy there is provided a roller 70 24 which is pivoted in a bifurcated arm 25. This arm extends forward and operates through the plate 18 and is beveled at its outer end at 26 and is adapted to be engaged by the hinged plate 20. Around the 75 arm 25 is coiled a spring 28 which engages the plate 18 and the bifurcated end of the arm 25. Above the roller 24 is an inked pad 30 and also below the roller is another inked pad 32. The lower inked pad forming a 80 trackway for the roller.

The roller shown in Fig. 3 is provided with raised signatures 34 on its periphery which run lengthwise of the roller. The number of such raised signatures 34 is not 85 more than two or three, and no two signatures appear diametrically opposite one another. The distance between the two inking surfaces or pads 30 and 32 is equal to the diameter of the roller 24 plus the depth of 90 a raised signature. Therefore, the roller can rotate over the track-way provided by the pad 32, until one signature surface or another engages with one inking surface or the other. If the contact is between a signature surface and the lower inking surface, the signature is inked during the rolling contact thereof with the inking surface. If the contact is between the upper inking surface and a signature, the signature surface is 95 lightly wiped over the upper inking surface and is inked thereby. These signatures are fac-similes of the signatures of the officers authorized to validate or sign a policy.

Facing and spaced from the rear of the 105 back casing 4 is a plate 35 and on top of casing 2 is a pin 36 on which the policies or documents are to be hung. In the base of the casing is a box provided with a door 40 which has a slot 42 therein for the pur- 110

pose of receiving the identification coupons incorporated in the policy. Also beneath the plunger 15 at the bottom of the casing is another box frame having a drawer 44. 5 This is provided with a lock 45 and over this is the angled front plate 50. 46 is the opening into which the coin 48 is entered.

The manner of operating my device is as follows: The party desiring an accident 10 policy removes the policy 38 from the pin 36 and places it between the end of the casting 4 and the plate 35 next to the plate. He then enters the coin 48 of the proper denomination, through the opening 46 and it drops vertically guided down the above described 15 channel which substantially fits its diameter formed by the conjunction of plates 7, 9, and 11, until it strikes into the center of the chute or groove 21 on the hinge plate 20.

20 Then the operator presses down upon the cap 12, which forces down the plunger 15 against the coin top and this forces down the hinge 20 and as it is brought down it engages the beveled end 26 of the bifurcated 25 arm 25 and forces back the roller 24 until one of the signatures 34 comes in contact with the policy, which rests against plate 35, and impresses the signature thereon at the proper place. As the roller advances to 30 make the impression it becomes inked by pads 30 and 32. After the impression is made, then the spring 28 comes into action and draws back the roller and the arm to a position shown in Fig. 2. When the coin 35 has been forced down and has brought the hinged plate 20 against the end 26 and forced the roller back to make the signature, then the coin passes on down the trough 21 and drops into drawer 44 beneath, but the 40 plunger is stopped by the cross arm 13 coming in contact with the upper end of the hinged plate 20. The spring 14 will then come into action and raise the plunger 15 to its normal position with bottom directly 45 above opening 46 which operation allows all parts to resume original position. The operator then takes the policy out and writes his name upon the identification coupon attached to the policy and pushes the coupon 50 through the slit 42 into the coupon box. It will be seen by this mode of construction that a party desiring an accident insurance policy can procure it in a very short space of time, and without any great delay or inconvenience.

Having now described my invention what I claim is:—

1. In a document identifying device, the combination with a casing, of an inked 60 trackway, a roller having a signature surface formed on its periphery in position to coöperate with said inked trackway, and a document holder provided across said cas-

ing, said document holder also lying in the path of movement of said roller to provide 65 an impression plate to coact with said signature surface.

2. In a document identifying device, the combination with a casing of a roller, an elongated inking surface providing a track- 70 way for said roller, a signature surface on said roller, an actuating device for pushing said roller over the trackway, whereby said signature surface becomes inked, a document holding element mounted at the end of said 75 casing and having an opening in communication with said trackway, said document holding element also acting as a backing for the document while the latter is being impressed by the signature surface on said 80 roller.

3. In a document identifying device, the combination with a casing, a multi-surfaced inked trackway, a roller operative between 85 said surfaces, signature surfaces formed on said roller and adapted to coöperate with the surfaces of said trackway, and a document holding element spaced from one end of said casing, said document holding element coming in the path of movement of 90 said roller to provide an impression plate behind the document.

4. In a document identifying device, the combination with a casing, a multi-faced trackway, a roller operative through said 95 trackway, inking surfaces on the faces of said trackway, signature surfaces on said roller, each of said signature surfaces being adapted to coöperate with one of said inking surfaces, means for moving said roller through said trackway, a document supporting device mounted in spaced relation to one end of said casing, the back of said document holding device appearing opposite the end of said trackway and constituting an 105 impression plate adapted to coact with said signature surfaces.

5. In a document identifying device, the combination with a casing, an inked track- 110 way provided in said casing, a roller operative over said trackway, a document holding device carried by one end of said casing, and appearing opposite the end of said trackway to constitute an impression plate for said roller, signature surfaces on said roller for 115 stamping documents held by said document holder, and a receptacle mounted in said casing for receiving detached portions of the document.

In testimony whereof I affix my signature 120 in presence of two witnesses.

FRANK B. REYNOLDS.
